UNITED STATES PATENT OFFICE.

NATHAN BARUCH, OF NEW YORK, N. Y.

DESIGN FOR A HAT-PIN OR ANALOGOUS ARTICLE.

51,914.

Specification for Design.

Patented Apr. 2, 1918.

Application filed December 5, 1917. Serial No. 205,676. Term of patent 3½ years.

To all whom it may concern:

Be it known that I, NATHAN BARUCH, a citizen of the United States, residing in the borough of Manhattan, city, county, and State of New York, have invented a new, original, and ornamental Design for Hat-Pins or Analogous Articles, of which the following is a specification, reference being had to the accompanying drawing, forming part thereof.

In the drawing Figure 1 is a plan view and Fig. 2 an elevation of a hatpin, showing my new design.

I claim:

The ornamental design for a hatpin, or analogous article, as shown.

NATHAN BARUCH.
